UNITED STATES PATENT OFFICE.

SILAS WILLIAM WOODLAND, OF ROXBORO, WASHINGTON.

CURRENT WATER-WHEEL.

1,290,466.

Specification of Letters Patent.

Patented Jan. 7, 1919.

Application filed January 10, 1918. Serial No. 211,145.

To all whom it may concern:

Be it known that I, SILAS WILLIAM WOODLAND, a citizen of the United States, residing at Roxboro, in the county of Adams, 5 State of Washington, have invented a new and useful Current Water-Wheel; and I do hereby declare the following to be a full, clear, and exact description of the invention, such as will enable others skilled in 10 the art to which it appertains to make and use the same.

This invention relates to an improved current water wheel, and one of the objects of 15 the invention is to provide a power wheel of this kind adapted to be mounted upon a bed of a stream of water and having means whereby it may be belted to any suitable source for generating power for running small machinery.

20 A further object of the invention is to provide a device of this kind, which may be manufactured for a small cost and sold at a reasonable profit, and which comprises improved features of construction.

25 One of the features of construction is the provision of a body member consisting of two sections secured together and having bearings, in which the stems of the propeller blades are mounted, so that said blades may 30 partially turn or rotate, whereby the blades may feather through the water on their return movements as the wheel rotates. Another feature of the invention is the provision of means for limiting the blades in 35 their feathering positions and in their positions when propelled by the water.

In practical fields the details of construction may necessitate alterations falling within the scope of what is claimed.

40 The invention comprises further features and combination of parts as hereinafter set forth shown in the drawings and claimed.

In the drawings:

Figure 1 is a plan view of the improved 45 current water wheel constructed in accordance with the invention.

Fig. 2 is a sectional view on line 2—2 of Fig. 1.

Fig. 3 is a detail view in perspective of a 50 portion of the body of the wheel, showing the mounting of one of the propeller blades.

Fig. 4 is a sectional view on line 4—4 of Fig. 3.

Referring more especially to the drawing, 55 1 designates a suitable supporting frame, which may rise upwardly from the

bed of a stream of water and may be anchored in any suitable manner. The current water wheel comprises the body 2 consisting of 2 two circular sections on plates 3 60 and 4. The lower section 4 is provided with a downwardly extending shaft, which is axially concentric with the body of the wheel. This shaft comprises a larger portion and a reduced portion 5 6 (which is 65 mounted in bearings 7 and 8 of the supporting frame 1) and an intermediate shoulder 9 which engages the top of the frame 1. This shoulder 9 together with the collar 10 (which is secured by a pin 11 to the reduced portion) engaging the under face of the top of the frame 1 prevents axial movement of the shaft of the circular section 4 of said body. The upper circular section 3 of the body has an upwardly extending 75 shaft 12 which is axially concentric with the body, and is designed to be of sufficient length to project above the surface of the water of the stream and may be mounted in a bearing (not shown). The upper end of 80 the shaft 12 is provided with a suitable pulley 13 to which a belt (not shown) may be connected for transmitting power to any suitable source for operating light machinery. By means of bolts 14 and nuts 15 the 85 two circular sections 3 and 4 are secured together. The adjacent faces of the circular sections are provided with radially disposed semi-circular recesses 16 and 17, which, when the circular sections 3 and 4 90 are fastened together, as shown, form cylindrical bearings for the stems 18 of the propelled blade. The upper circular section of the body is provided with rectangular openings 19, which are elongated, and are arranged concentrically with the center of the body of said power wheel. The stems 18 of the propeller blades are provided with lateral extending lugs 20. The upper face of the circular section 4 of the body is provided 100 with rectangular recesses 21, which adjoin the semi-circular recesses 17, and are arranged concentrically with the center of the body of the wheel and in registration with the openings 19. When the blades are 105 in operative position, whereby the water may propel the wheel, the lugs 20 are disposed perpendicular and are designed to abut the ends 22 of the ends 19, so as to hold the blades in such operative positions. When the propellers feather the water the lugs 20 rest in and engage the recesses 21, 110

thereby holding the blades in such feathered positions. The stems are provided with longitudinally bifurcated extensions 23, in which the blades 24 are secured by rivets or the like 25. The blades 24 upon their opposite faces are provided with strips 26 and 27, which are secured by the rivets or the like 28, for reinforcing and strengthening said blades, whereby the blades may 10 withstand the strain exerted by the water.

The invention having been set forth what is claimed as new and useful is:—

15 In a current water wheel, a circular body consisting of a pair of circular disk sections, means for fastening the disk sections together, the adjacent faces of the disk sections having radially disposed registering recesses semi-circular in cross section forming cylindrical bearings, the inner face 20 of one of the disk sections having rectan-

gular recesses adjoining the semi-circular radial recesses, the other circular disk sections having openings concentric with the center of the body and registering with the rectangular recesses of said inner face of the 25 other disk section, propeller blades having stems rockable in the cylindrical bearings, said stems having lugs to engage certain ends of said rectangular openings and to engage said rectangular recesses to limit the 30 blades in their operative and feathering positions.

In witness whereof I have signed my name to this specification in the presence of two subscribing witnesses.

SILAS WILLIAM WOODLAND.
